(57) **CLAIM**

The ornamental design for a mounting bracket as shown and described.

DESCRIPTION

FIG. 1 is a front perspective view of the presently claimed design.

FIG. 2 is a side view of the presently claimed design.

FIG. 3 is an opposite side view of the presently claimed design.

FIG. 4 is a front view of the presently claimed design.

FIG. 5 is a rear view of the presently claimed design.

FIG. 6 is a top view of the presently claimed design; and,

FIG. 7 is a bottom view of the presently claimed design. The broken lines in FIGS. 1-7 are for the purpose of illustrating portions of the mounting bracket that form no part of the claimed design.

1 Claim, 6 Drawing Sheets
